UNITED STATES PATENT OFFICE.

HARRY E. McCANDLESS, OF ROCHESTER, NEW YORK, ASSIGNOR TO KENNEDY-MCCANDLESS CORPORATION, OF ROCHESTER, NEW YORK, A CORPORATION OF NEW YORK.

DETACHABLE TOILET SEAT FOR INFANTS.

Application filed January 25, 1924. Serial No. 688,452.

To all whom it may concern:

Be it known that I, HARRY E. McCANDLESS, a citizen of the United States of America, residing at Rochester, in the county of Monroe and State of New York, have invented certain new and useful Improvements in Detachable Toilet Seats for Infants, of which the following is a specification.

10 My invention relates to an infant's toilet seat, and has for its purpose to provide a structure of this character which is readily attachable to or removable from the conventional toilet seat.

15 A more particular object of my improvement is to provide a construction that permits of quickly and firmly attaching an infant's toilet seat in place on a permanent seat, eliminating danger of the infant's seat 20 being accidentally displaced.

25 A further purpose of the invention is to enable detachably securing an infant's toilet seat in place, without the necessity of 30 marking the permanent seat to which it is attached, or permanently securing any attaching devices to the latter.

An additional object of my improvement 35 is to provide a structure including an automatic clamping member that engages the permanent seat and holds the temporary seat in place thereon, the clamping member being operated by the elevating or lowering of the cover portion on the temporary seat.

The invention also includes certain other 40 improved features, all of which will appear clearly from the following description when read in conjunction with the accompanying drawings, the novel features being pointed out in the claims following the description.

45 In the drawings:

Figure 1 is a side elevation illustrating a preferred embodiment of my invention, and showing the parts in the position occupied when the cover portion is raised and 45 the clamping member engaged with the permanent seat;

Figure 2 is a plan view of the same;

Figure 3 is a side elevation of the structure, with the cover portion lowered;

50 Figure 4 is a plan view of the same;

Figure 5 is a bottom plan view of the same;

Figure 6 is a vertical sectional view on line 6-6 of Figure 2;

Figure 7 is a sectional view on line 7-7 55 of Figure 6;

Figure 8 is an enlarged detail view, and

Figure 9 is a sectional view illustrating the connection for the suction cup.

Referring more particularly to the drawings, in which like reference characters refer to similar parts throughout the several views, 1 designates a conventional form of permanent toilet seat to which the infant's temporary seat is attached when desirable. 60 The structure constituting my invention includes a seat portion 2 and a cover portion 3, which parts are connected by hinges comprising the leaves 4 attached to the cover portion and leaves 5 attached to the seat portion. The cover portion is recessed at the bottom corner of its rear edge as shown at 6, to receive the barrel portions 7 of the hinge, so that when the cover portion is in its vertical position, as illustrated in Figure 75 1, its rear edge 8 engages the upper surface of the seat portion, and prevents the cover portion from being forced too far backwardly when opening.

The device is held engaged with a permanent seat or support 1, principally by a clamping member including a clamping portion 9 that engages the seat 1 and an operating portion 10. The clamping member is formed of a single piece of metal bent 85 upon itself to afford said clamping portion 9 and the operating portion 10, and to pivotally engage a supporting element preferably in the form of a rod 11, the ends of which are held in place by suitable attaching devices 12. The clamping member is held in proper pivotal relation with the supporting element 11 by means of integral lugs 13 struck from the operating portion 10 and engaging 90 said supporting element, as shown in Figure 7, while 14 is a spring of suitable formation with its ends held by the attaching devices 12 to the underside of the seat portion, said spring engaging the operating portion 10 of the clamping member and 100 functioning to retain the latter normally against the seat portion, as shown in Figure 3, with the clamping member in releasing position.

The clamping member is operated automatically by the cover portion, which when elevated moves it to clamping position, and when lowered permits the spring 14 to actu-

ate it to releasing position. This is preferably accomplished through the instrumentality of a pin 15, slidably arranged in the seat portion with its upper end in the path 5 of the rear edge of the cover portion, so that as the latter is elevated, the pin 15 is depressed. The lower end of the pin has a 10 slidable connection with the operating portion 10 of the clamping member, the latter 15 preferably being slotted as at 16 to receive said pin. 17 is a head on the lower end of the pin which holds it in engagement with the clamping member, and causes the latter to be operated to clamping position by the pin, the slot 16 permitting the necessary 20 sliding relationship between the pin and the operating portion 10 of the clamping member.

In conjunction with the clamping member 25 already described, the device is retained on the permanent seat by means of suction cups 30 preferably of rubber, and designated at 18. The cups 18 are arranged at the forward part of the seat portion, and each includes 35 a shank 19 provided with annular ribs 20. The shank 19 engages a recess in the seat portion, and the cup is held in place by suitable cement, which forms a tight interlocking connection with the ribs 20 on the shank. 40 The seat is applied in the manner shown in Figure 3, first pressing the forward part downwardly against the permanent seat, causing the suction cups 18 to adhere thereto. Following this, the cover portion 3 is 45 elevated as in Figure 1, causing the clamping member to tightly engage the under side of the permanent seat, as shown in Figure 1. It is desirable that when the cover portion 3 is elevated, it be automatically locked 50 in such position to prevent accidental lowering, and to accomplish this I employ connecting bars 21 and 22 pivotally connected to each other at 23, the bars 21 being pivoted to the cover portion at 24 and bars 22 pivot- 55 ed to the seat portion at 25. Such connecting bars are preferably provided at both sides of the cover portion to serve as a protecting and retaining means for the infant, while 26 designates a locking bar which may 60 be provided at one side only, and acts to hold the cover portion in its upright position. To this end, the locking bar 26 is pivoted to the bar 22 and is slotted at 27 to engage a pin 28 on the bar 21. The slot 27 has a vertically 65 extending recess or pocket 29 at its outer end to engage the pin 28, and when the cover is elevated to its uppermost position, the slot 27 slides along the pin 28 until the latter is reached by the recess 29, whereupon 70 the bar 26 drops to the position shown in Figures 1 and 8, with the pin 28 at the top of the recess 29. In this position, the locking bar 75 prevents the cover portion 3 from being moved forwardly, and to permit such movement, the locking bar 26 must first be

elevated to permit the pin 28 to reengage the slot 27, after which the cover portion can be lowered.

The invention is susceptible of various changes and modifications without departing from the novel features herein disclosed, and forming the basis of my improvements, and this application is intended to cover any such departures as may come within the intended scope of my invention or of the following claims.

I claim:

1. In an infant's toilet seat, the combination with a seat portion and a cover portion, of a clamping member movably arranged on the seat portion, and means automatically controlled by the cover portion for actuating the clamping member.

2. In an infant's toilet seat, the combination with a seat portion positionable on a support, a clamping member carried by the seat portion, and means automatically controlled by the cover portion for causing the clamping member to engage said support and retain the seat thereon.

3. In an infant's toilet seat, the combination with a seat portion and a cover portion, of a clamping member pivotally mounted on the seat portion, and means automatically controlled by the cover portion for actuating the clamping member to clamping and releasing positions respectively when the cover portion is raised and lowered.

4. In an infant's toilet seat, the combination with a seat portion and a cover portion, of a clamping member pivotally mounted on the underside of the seat portion, and a pin extending through the seat portion having its lower end connected to the clamping member and its upper end lying in the path of the cover portion so as to be actuated thereby when the latter is raised.

5. In an infant's toilet seat, the combination with a seat portion and a cover portion, of a clamping member pivoted on the underside of the seat portion, and a pin extending through the seat portion with its upper end in the path of the cover portion so as to be actuated thereby when the cover portion is elevated, the lower end of said pin having a sliding connection with the clamping member and operable to move the latter to clamping position.

6. In an infant's toilet seat, the combination with a seat portion and a cover portion, of a clamping member movably positioned on the seat portion and actuated by the cover portion to clamping position when the cover portion is elevated.

7. In an infant's toilet seat, the combination with a seat portion and a cover portion, of a clamping member movably positioned on the seat portion and actuated by the cover portion to clamping position when the cover portion is elevated, said clamping

member comprising an integral piece of metal bent upon itself to pivotally engage a supporting element, lugs struck from the clamping member and acting to retain the same in pivotal relation to the supporting element, and a spring acting to return the clamping member to normal position when released.

8. In an infant's toilet seat, the combination with a seat portion and a cover portion, of a clamping member arranged on the underside of the seat portion and comprising an integral piece of metal bent upon itself to pivotally engage a supporting element and affording an operating portion lying normally against the underside of the seat portion and a clamping portion, lugs struck from said operating portion and engaging the supporting element to hold the clamping member in pivotal relation therewith, a spring engaging said operating portion and holding it normally against the seat portion, said operating portion being slotted, and a pin slidably arranged in the seat portion with its upper end in the path of the cover portion and its lower end having slideable engagement with said slot in the clamping member so as to actuate the latter when the cover portion is elevated.

9. In an infant's toilet seat, the combination with a seat portion and a cover portion, of a clamping member arranged at the rear of the seat portion and controlled by the cover portion, and suction retaining cups arranged at the front of the seat portion.

10. In an infant's toilet seat, the combination with a seat portion and a cover portion, of a clamping member arranged at the rear of the seat portion and controlled by

the cover portion, and suction retaining cups at the front of the seat portion, each of said suction cups comprising a shank having annular ribs, said shank being cemented in an opening in the seat portion.

11. In an infant's toilet seat, the combination with a seat portion and a cover portion, of a pair of connecting bars pivoted to each other, one having pivotal relation with the seat portion and the other with the cover portion, and a locking bar pivoted to one of said connecting bars and having a pin and slot connection with the other of said bars and operating automatically to lock the cover portion in uppermost position.

12. In an infant's toilet seat, the combination with a seat portion and cover portion, of a pair of connecting bars pivoted to each other and having pivotal connection with the seat and cover portions, a pin on the upper of said bars, and a locking bar pivoted to the lower connecting bar and having a slot engaging said pin, said slot terminating at one end in a vertical recess which receives said pin and automatically locks the cover portion in vertical position.

13. In an infant's toilet seat, the combination with a seat portion, of a clamping member at the rear of the seat portion for engaging the underside of a support, and suction retaining cups at the front of the seat portion for engaging the upper side of said support.

In testimony whereof, I have hereunto signed my name.

HARRY E. McCANDLESS.
